(57) **CLAIM**

The ornamental design for a SMD clamp, as shown and described.

DESCRIPTION

FIG. 1 illustrates a perspective top and left side view of the first embodiment of the SMD clamp showing the new design.

FIG. 2 illustrates a front face view of the SMD clamp in FIG. 1.

FIG. 3 illustrates a rear face view of the SMD clamp in FIG. 1.

FIG. 4 illustrates a left side view of the SMD clamp in FIG. 1.

FIG. 5 illustrates a right side view of the SMD clamp in FIG. 1.

FIG. 6 illustrates a bottom view of the SMD clamp in FIG. 1; and,

FIG. 7 illustrates a top view of the SMD clamp in FIG. 1. The broken lines in the drawings illustrate portions of the SMD clamp that form no part of the claimed design.
